[57] CLAIM

The ornamental design for an elbow cover for insulated pipework, as shown and described.

DESCRIPTION

FIG. 1 is a front elevational view of an elbow cover for insulated pipework showing my new design;

FIG. 2 is a rear elevational view thereof;

FIG. 3 is a top plan view thereof;

FIG. 4 is a right side elevational view thereof;

FIG. 5 is a left side elevational view thereof;

FIG. 6 is a cross sectional view taken on line 6—6 of FIG. 4;

FIG. 7 is a cross sectional view taken on line 7—7 of FIG. 4; and

FIG. 8 is a perspective view thereof showing the cover in an open position.

FIG. 1

FIG. 3

FIG. 2

FIG. 5

FIG. 4

FIG. 6

FIG. 7

FIG. 8

UNITED STATES PATENT AND TRADEMARK OFFICE
CERTIFICATE OF CORRECTION

PATENT NO. : DES 312,499
